GAS BURNER

Henry C. Caldwell, Buffalo, N. Y., assignor, by
mesne assignments, to Hendwell Burner Cor-
poration, Buffalo, N. Y., a corporation of New
York

Application November 6, 1935, Serial No. 48,537

2 Claims. (Cl. 158—99)

My invention relates in general to gas burners and more particularly to burners which are applicable to gas ranges, hot water heaters, and similar uses. For purposes of comparison reference herein is made to the United States Patent No. 2,116,096, issued to me May 3, 1938, for a Method of burning gas.

It is well known to those skilled in the art that in gas burners of the Bunsen type, the gas is let into a mixing tube which is usually of Venturi form so as to increase the velocity of the gas and air passing therethrough. Air is admitted immediately back of the outlet of the gas spud in adjustable quantities. The mixture then passes through a mixing tube and is burned above a number of small, restricted outlets known as ports. It is well known that if sufficient air is supplied at the mixer of such a Bunsen burner, the burner will tend to backfire, igniting the gas at the spud or nipple. To prevent this, insufficient air is supplied through the mixing tube and secondary air is then added at the small ports above which the elements of combustion are burned. In such Bunsen practice, the gas flowing into the mixing tube causes air to be induced through a restricted air opening into the tube. Such induction of air causes a slight reduction in the velocity of the gas; the travel of the elements of combustion through the rather long mixing tube further reduces the velocity; and the passage through and burning above the small ports at the outlet or burning point of the burner also decreases the velocity.

In my burner it is essential that the gas travel far enough through the free air or through a protective chamber sufficiently large to supply more than enough air to create a proper mixture of combustible elements and that the speed of travel of these elements to the point of ignition and combustion shall be maintained as great as possible.

One of the principal objects of my invention has been to provide a burner in which gas, as it comes from the main, passes through free air a distance substantially sufficient to attain a proper mixture, at which point it is burned without restriction and without loss of the velocity given to the combustion elements by the gas as it flows from the main.

Another object has been to provide a burner in which there shall be sufficient air around the stream of gas, so that the gas may be supplied with ample air without causing an appreciable reduction of the velocity of the gas coming from the supply spud;

Another object has been to provide a burner in which there shall be an unrestricted flow of combustible elements at maximum speed.

A further object of my invention is to provide a burner in which combustion of the fuel elements shall occur at the point where the gas and air have been mixed sufficiently to produce a substantially combustible mixture.

Moreover, in my burner fluctuations of pressure in the gas main do not affect the combustion and do not result in the creation of soot and smoke.

Furthermore, due to the fact that in my burner the gas passes through the free air a sufficient distance, substantially all of the air needed to support combustion is provided without the necessity of providing for secondary air at the point of ignition and combustion.

In my invention I provide a spreader arranged above the mouth of the burner and it is a characteristic of my invention that ignition and combustion may occur substantially within the mouth of the burner and below the spreader thereof, but such ignition and combustion usually occur immediately outside of the burner.

It is further characteristic of my burner that the air, which is supplied to the stream of gas in ample quantities to produce combustion at the desired place, is controlled at the mouth of the burner.

Another object has been to provide a burner in which combustion shall occur either inside the burner or outside thereof, whereby backfiring will be prevented.

Moreover, my burner is of such a nature that the article being heated, such as a cooking utensil or the like, may be placed directly on the top of and in contact with the spreader, whereby the heat generated is transmitted to the article being heated by conduction as well as by radiation and reflection.

Another object has been to provide a burner which shall be adjustable to adapt the same to use with various kinds of gas.

A further object is to provide a burner having its ports and outlet passages so arranged that the burner cannot easily become slogged. In the event that dust does accumulate in the body of the burner, the parts are so designed that they may be easily disassembled and cleaned.

Moreover, my burner is of such construction that it may be conveniently used to replace burners of various stoves, ranges, and heating appliances now in use.

The above objects and advantages have been

accomplished by the device shown in the accompanying drawing, of which:

Fig. 1 is an exterior view of one form of my invention.

5 Fig. 2 is a sectional view thereof taken on line 2-2 of Fig. 1.

Fig. 3 is a bottom, sectional view taken on line 3-3 of Fig. 2.

10 Fig. 4 is a fragmentary, exterior view of a modified form of invention showing a different type of spreader.

While my burner will function if the gas is projected through free air, it is, of course, necessary, in order to meet the Fire Underwriters and 15 American Gas Association requirements, that a protective body be provided around the gas stream for protecting the gas stream against outside disturbances. As shown in the drawings, therefore, 20 my burner comprises a single-chambered body 19 which is tubular in form and provided with a central opening 11 which is preferably conical in shape and flaring downwardly. The body, therefore, provides an air space 12 which is relatively 25 large and which is so proportioned that it provides more air than is required by the gas to properly support combustion. The mouth 13 of the burner is formed at the upper end of the opening 11 in the body. The body is formed at its 30 upper end with a neck 14 which is exteriorly screwthreaded.

The burner body is carried by a body support 16 which have an upstanding ring 17 which encircles the bottom edge of the body 16 and serves to centrally support the same. The body support is also provided with a central hub portion 18 which is connected to the ring portion 17 by means of a plurality of arms 19 thus leaving air spaces 20 between the ring portion and the hub portion for the entrance of air. The hub portion is provided 40 with an interior screwthread which engages with an exteriorly screwthreaded gas outlet pipe 24. This outlet pipe is of considerable length so that the spud 25, either formed thereon or attached thereto, may be moved up or down within the air 45 space 12 of the tube by rotation of the body support upon the pipe, for purposes to be hereinafter described. A lock nut 21 is preferably provided on the outlet pipe for locking the position of the body support after it has been adjusted. The outlet pipe 24 is provided with any suitable type of 50 shut-off cock 26 by which the gas may be either turned on or off, or may be regulated if desired.

The neck 14 of the body is of considerable length and upon its screwthreaded exterior is 55 mounted an adjusting ring 27. This ring is provided with an upstanding wall 28 which is formed with a plurality of notches 29 in its edge surface. These notches extend, as clearly shown in Fig. 2, a considerable distance along the peripheral surface 60 of the ring. The wall 28 is relatively thin and it is bored out so as to provide an annular recess 35 for the reception and support of the lower end of a spreader 36. This spreader is provided with a lower, substantially convex surface 37 and an upper substantially flat surface 40 and is centrally arranged above the mouth 13 of the burner. Between the lower surface 37 of the spreader and the upper surface 38 of the neck is provided 65 an annular space which is varied by the rotation of the ring 27 for controlling the amount of air passing through the mouth of the burner. A lock nut 33 is placed upon the neck 14 and is engageable with the adjusting ring to lock it when 70 it has been adjusted to the desired position. I

have found it advantageous to make the spreader 36 of copper; since, as above pointed out, the article to be heated, which may be a cooking utensil, may be placed in direct contact with the spreader and be supported thereby if desired, whereby heat which is generated is conducted to the article by conduction as well as by radiation and reflection.

Referring now to the form of invention shown in Fig. 4, an adjusting ring 45 is provided and it is screwthreaded to the neck 14 of the body 10 of the burner. Arranged above the adjusting ring is the spreader 46 which is a relatively thin plate as compared to the other form of invention and which is preferably provided with a convex lower surface 47 and a substantially flat top surface 49. The spreader may be held in interspaced relation with the adjusting ring 45 by means of a plurality of separating pins 48. In this form of apparatus, the annular space surrounding the mouth of the 20 burner body is formed between the upper surface 33 of the neck and the lower convex surface 47 of the spreader and the size of such space may be varied by rotating the ring 45.

While my burner is, of course, designed so that it may be operated at a rate of gas flow which is lower than the rate for which the burner was designed, the highest efficiency possible is brought about by operating the burner at its maximum rate of gas flow. Under these conditions the gas 30 in the main will be supplied to the gas outlet pipe and to the orifice thereof at the maximum gas main pressure with the result that the gas stream coming from the gas orifice will pass through the body at maximum velocity. As the gas stream 35 emerges from the orifice of the gas outlet pipe and passes into the air space 12 of the body 19, it is mixed with free air in this space. The burner is first adjusted for the kind of gas to be burned by screwing the body support 16 up or down 40 upon the gas outlet pipe to a point where the upper end of the mouth 13 of the body will be at such distance from the outlet of the gas orifice in the pipe as to bring about, within narrow limits the most efficient combustible mixture. The body is then locked by means of the lock nut 21 and the burner does not thereafter have to be adjusted for the particular gas upon which it is used. Since the amount of air passing through the burner and, therefore, the final character of the combustible mixture is controlled at the mouth of the burner, the final adjustment of the burner is made by means of the adjusting ring 27 which governs the size of the annular outlet space of the burner. It will thus be seen that the gas under the maximum gas main pressure is projected into and through free air and thus takes up sufficient air to bring about an efficient combustible mixture at the outlet space of the burner which is formed between the upper surface 38 of the neck and the curved surface 37 of the spreader. Ignition and combustion may occur at substantially this same place and the speed of travel of the gas and the mixture is thereby not diminished in any way before combustion occurs, except the slight reduction obviously resulting from contact of the gas stream with the surrounding air. Combustion, therefore, occurs substantially within the mouth of the body and below the spreader 36. The heated products of combustion 55 then pass outwardly through the openings formed by the notches 29 in the wall 28 of the adjusting ring and between the lower edge of the spreader body. As hereinbefore pointed out, the article being heated consisting, for instance, of a cooking 60 utensil, may be placed in direct contact with the spreader and be supported thereby if desired, whereby heat which is generated is conducted to the article by conduction as well as by radiation and reflection.

utensil or the like, may be placed directly upon the top of and in contact with the spreader so that the heat generated is transmitted not only by conduction but also by radiation and reflection. Since ignition and combustion may occur within the burner mouth, my burner cannot backfire and any turning down of the gas at the gas cock 26 will serve to lessen the spread of the flame and will even draw the point of combustion down 10 into the air space 12 of the burner.

From the foregoing it will be obvious that an efficient combustible mixture is brought about in my burner when the gas, under substantially full gas main pressure, has been projected through 15 the free air space a sufficient distance to take up substantially all the air needed to support combustion when ignition and combustion takes place, which is usually substantially within the mouth of the burner. Substantially no second- 20 ary air, therefore, is needed since practically all the air is initially supplied to the stream of gas as it passes up through the free air space 12 of the burner body. While ignition and combustion may occur substantially within the mouth of the 25 burner and below the spreader 36, it usually occurs immediately outside of the spreader.

When my burner is to be used, the body support 16 having been set for the kind of gas being used and the existing pressure thereof, the final character 30 of the combustible mixture, as hereinbefore set forth, is controlled by the adjusting ring 27 which governs the size of the annular outlet space of the burner. As hereinbefore pointed out, substantially all the air necessary to support combustion within the burner is supplied to the stream of gas within and as it passes through the free air space 12. The regulation just above referred to controls the amount of air which is allowed to pass through the burner, the amount 35 of gas remaining constant under normal conditions. By increasing the size of the outlet space, the amount of air in the mixture as it reaches the combustible point within the burner is increased, whereas if this space is decreased by 40 screwing down the adjusting ring, the amount of air at the place of combustion is decreased. In my burner, therefore, the supply of air is controlled entirely at the outlet thereof.

In the appended claims where I use the term 50 "protective" as applied to the body, I mean a body which is of such a size that the quantity of air which it surrounds will be more than enough to mix with the gas to produce a substantially per-

fect combustible mixture. In other words, the gas will be projected through a substantially free air space. Another function of the protective body is to provide protection for the gas stream against outside disturbances.

5

While I have shown and described the bottom surface of the spreader as convex, the convexity thereof may be made greater or less as desired, or such surfaces may be made substantially flat. Obviously, these and other modifications of the 10 details herein shown and described may be made without departing from the spirit of my invention or the scope of the appended claims, and I do not, therefore, wish to be limited to the exact embodiment herein shown and described, the form 15 shown being merely a preferred embodiment thereof.

Having thus described my invention, what I claim is:

1. A gas burner comprising a single-chambered, 20 protective body, said body being open at its lower end and having an open mouth, said body having a smooth, continuous, inner wall for the unobstructed passage of the gas and air, a gas outlet pipe having an orifice centrally arranged in co- 25 operative relation with the lower end of the body, a spreader arranged in cooperative, spaced relation with the upper end of the body, said spreader being so shaped and proportioned that all of the parts thereof are located above and outside of 30 the body, and adjustable means located at the outlet of the burner body for regulating the amount of air entering the lower end of the burner body and passing through the outlet.

2. A gas burner comprising a single-chambered, 35 protective body, said body being open at its lower end and having an open mouth, said body having a smooth, continuous, inner wall for the unobstructed passage of the gas and air, a gas outlet pipe having an orifice centrally arranged in co- 40 operative relation with the lower end of the body, an adjusting ring carried at the outlet end of the body for regulating the amount of air entering the lower end of the burner body and passing through the outlet, and a spreader secured to the 45 ring and arranged in cooperative relation with the mouth of the body, said spreader being so shaped and proportioned that all of the parts thereof are located above and outside of the body, whereby the size of the outlet space of the burner 50 may be adjusted.

HENRY C. CALDWELL.
